LOCOMOTIVE TENDER

Elmer E. Hicken, Collingswood, N. J.

Application February 27, 1938, Serial No. 65,992

12 Claims. (Cl. 105—414)

This invention relates generally to a frame and tank for locomotive tenders and more particularly to an improved combination of structural shapes and plates so formed and interrelated 5 that the same may be effectively assembled and welded together to form an efficient integral structure.

Heretofore it has been customary to make a tender frame of an integral steel casting to which 10 is secured a tank consisting of structural shapes and plates riveted or welded to each other and to the underframe, the underframe being made with a solid or water tight bottom.

The cast underframe of such prior arrangements is expensive on account of its size and 15 many detail cored portions, is of considerable weight due to the thickness of the sections and is practically prohibitive in cost when an order for a single tender is required. Such prohibitive 20 cost is due to requiring a complete set of patterns or core boxes which would only be used once.

It is one object of my invention to provide a tender having an underframe that is less expensive and yet fully as effective as cast underframes and one that can be applied to an order 25 for a single tender at a reasonable cost. To accomplish this I utilize novel forms and arrangements of shapes and plates so interconnected and related that they may be efficiently 30 and effectively welded to form the underframe and tank in a manner which creates a very effective single integral structure.

Other objects and advantages will be more apparent to those skilled in the art from the 35 following description of the accompanying drawings in which:

Fig. 1 is a longitudinal vertical section of a tender embodying my improved underframe and superstructure taken substantially on the line 40 1—1 of Fig. 2;

Fig. 2 is a horizontal section taken substantially on the line 2—2 of Fig. 1;

Fig. 3 is an end elevation of the front end of the tender and underframe, the front of the 45 tender being at the right end of Figs. 1 and 2;

Fig. 4 is a longitudinal vertical section of my improved coal slide guide stiffener taken on lines 4—4 of Figs. 2 and 3;

Fig. 5 is a perspective looking down on my 50 improved underframe shown partly in section and with certain parts omitted for clarity;

Fig. 6 is an enlarged fragmentary perspective with parts broken away to show the details of 55 construction of the rear draft rigging and its relation to the underframe structural elements;

Fig. 7 is an enlarged fragmentary broken away perspective of my improved bolster;

Figs. 8 and 9 are perspectives of the upper and 60 lower T members of the bolster;

Fig. 10 is a longitudinal section taken substantially on the line 10—10 of Fig. 7;

Fig. 11 is a longitudinal section taken on the line 11—11 of Fig. 5 and on line 11 of Fig. 7 and showing a top filler piece which is omitted from 5 Figs. 5 and 7 for clarity;

Fig. 12 is a horizontal section taken on the line 12—12 of Fig. 11;

Fig. 13 is a longitudinal vertical section showing a modified form of bolster, the location of 10 the section corresponding generally to that of Fig. 10 on line 10—10 of Fig. 7;

Fig. 14 is a further modified form of bolster construction, the view being taken transversely of the underframe on the line 14—14 of Fig. 15; 15

Fig. 15 is a longitudinal vertical section taken substantially on line 15—15 of Fig. 14;

Fig. 16 is a fragmentary perspective partly broken away to show details of construction of the forward draw bar housing; 20

Fig. 17 is a perspective of a draw bar pin bushing;

Fig. 18 is a perspective of one of the side pieces or sills of the forward draw bar housing;

Fig. 19 is a perspective of the bottom plate of 25 the same;

Fig. 20 is a perspective of an intermediate horizontal plate of the same;

Fig. 21 is a perspective of the other side piece or sill which is complementary to the side piece 30 shown in Fig. 18; together with my improved tank valve well on the outside of the side piece;

Fig. 22 is an end elevation of the rear draft rigging housing, partly broken away to show 35 details of construction;

Fig. 23 is a longitudinal vertical section taken on line 23—23 of Fig. 22;

In the particular embodiment of the invention, such as is disclosed herein merely for the purpose of illustrating one specific form among 40 possible others that the invention might take in practice, I have shown in Fig. 1 an underframe generally indicated at 1 carrying a tank generally indicated at 2. The underframe 1 as more clearly shown in Fig. 5 includes two longitudinal I-beams 3 forming center sills extending for the entire length of the frame by passing through a front end sill 4 and a rear end sill 5, both of which end sills are I-beams. The end 45 sills are of slightly greater depth than the center sills 3 to permit the web of the end sill I-beams to be cut out to the cross-sectional shape of the center sills to receive the same. Two side sills 6 extend for the entire length of the underframe but terminate in abutting relation to the end 50 sills adjacent their ends and just beneath the upper flanges thereof. As shown in Fig. 5, the side sills 6 are approximately only one-half the depth of the end sills.

As shown in Figs. 5, 6 and 11, there is provided 60

a bottom cover plate generally indicated at 9. This bottom plate is not continuous but is in three sections for reasons which will be noted later. However, it will be noted in Fig. 5 that 5 this plate is supported against the under side of the lower flanges of center sills 3 while the outer edges of the bottom plate rest on top of the lower flanges of side sills 6. This bottom plate is relatively much thicker than the balance 10 of the tank structure which will be described hereinafter as it must carry the weight of the water between unsupported points. One section of the bottom plate extends from end sill 4 to a front bolster 10, Fig. 1. Another section 15 extends from bolster 10 to a rear bolster 11 while the third section extends from bolster 11 to rear end sill 5.

The bolsters 10 and 11 are identical in construction and hence it will suffice to describe 20 only one which is shown in Figs. 7, 10 and 11. Referring to Fig. 7, the bolster comprises two upper T's 12 and 13 extending transversely of the under frame. These T's are spaced with respect to the longitudinal axis of the under frame. 25 The stem 14 of each T is coped as indicated at 15, Fig. 8, to fit around the top flange of side sills 6 while the intermediate portion 16 is coped to fit around the top flange and web of the center sills 3. The T's 12 and 13 are placed in their 30 assembled position by being slipped over the ends of the sills. A pair of lower T's 17 and 18, Fig. 10, are provided in vertically opposed relation to the upper T's 12 and 13. However, the lower T's have a horizontal central portion immediately 35 below the center sills and then are bent upwardly as indicated at 19, Figs. 7 and 9. The outer ends of the T's 17 and 18 are coped as indicated at 20, Fig. 9, to rest upon and fit around the upper surface of the lower flanges of side 40 sills 6. The coping 20 is such that the ends 21 of the outside T flange abut against the edge of the lower flange of the side sills 6. The stem 22 is coped at two places as indicated at 23 to fit around the lower flanges and web portions 45 of the center sills 3 in the same manner that the upper T's 12 and 13 are coped. The lowermost portion of the openings 23 is spaced as indicated at 24 from the T flanges to permit bottom plate 9 to be interposed between the T 50 flanges and the bottom of the center sills. The inner flange 25 extends only across the bottom of center sills 3 whereas the outer flange 26 extends for the full length of the T's. As shown in Figs. 11 and 12, a rectangular plate 28 is interposed between the lower flanges of center sills 3 and the shortened T flanges 25, thereby 55 providing a base for a center pin 29, Fig. 11.

As shown in Figs. 7, 9 and 11, the short flanges 25 of T's 17 and 18 extend toward each other 60 beneath plate 28, while the full length flanges 26 extend away from each other to support the various portions of the main bottom walls 9.

The base plate 28 and the T's 12, 13, 17 and 18 are all vertically reinforced in the following 65 manner. Vertical plates 31 connect the stems of the opposed T's in the space between the center sills 3. These vertical plates have been omitted from Fig. 7 for clarity. Similar vertical plates 31', Fig. 10, extending from the outside of the center sills to the inside of the side sills 6, connect the stems of the remaining portion of the upper and lower T's. Such plates may be laid 70 flat against the sides of the stems as it will be noted in Figs. 7 and 9 that the lower stems are cut as at 32 to permit the upper and lower stems 75

to contact in aligned relation with each other at their outer ends. To directly reinforce the center plate 28, a vertical plate 33, Figs. 11 and 12, extends transversely between the webs of center sills 3. Similar plates 34 and 35 extend between plates 31 and 33 at right angles thereto. In plan view as shown in Fig. 12, plates 33, 34 and 35 form a cross, thereby firmly supporting base plate 28, Figs. 11 and 12.

To laterally reinforce the vertical plates 31 which connect the stems of T's 12, 13, 17 and 18 and also to provide side bearings for trucks, I have provided as shown in Fig. 10 a horizontal H beam 37 whose flanges are supported against plates 31'. These H beams 37 extend horizontally from the outer surface of the web of center sills 3 outwardly to the inner surface of the web of side sills 6. The lower flange of the H beam near side sills 6 is tapered at 38, Fig. 7, to permit the H-web to rest on the inner surface of the lower flange of the side sills 6. Wearing plates 39 for a side bearing 40 of a truck are disposed on the under side of the web of H beams 37. Ample room is provided to receive the side bearings 40 due to the fact that the inner flanges of the lower T's 17 and 18 are cut away as clearly shown in Fig. 9, thereby leaving only the short flange portion 25 extending beneath the center sills.

In Fig. 13, which is a modification of Fig. 10, 30 the vertical plates 31 of Fig. 10 are eliminated and instead thereof the flanges 41 of an H beam 37' directly connect the stems 22 and 14 of the T's 13 and 17 and 12 and 18. The outer ends of the H-beams 37' and the lower flanges thereof 35 adjacent the side sills will be tapered in the same manner as indicated at 38 in the Fig. 7 form.

In the still further modification as shown in Figs. 14 and 15, there is substituted for T's 12, 13, 17 and 18 a pair of I beams 43 and 44, Fig. 40. 15. To adapt the I beams to the tapered construction of the bolster, a plain I beam of greater depth than center sills 3 has its web cut out and coped around the transverse configuration of the center sills 3-3 as indicated at 45, Fig. 14, whereby the I beam rests directly on the top flange of center sills 3. The lower flange 51 of the I beam is spaced from the lower flanges of the center sills 3 to permit insertion of the lower 50 cover plate or tank bottom 9. To create the tapered formation 47, Fig. 14 a long V portion indicated by dot-dash lines 48 is cut out of the web of the plain I beam after which the lower portion of the I beam adjacent the center sills 55 is heated and bent upwardly so that the opposed edges abut against each other and are welded as indicated at 49, Fig. 15. The ends of the web and flanges of the reformed and bent-up I beams are coped out as indicated at 50 to fit around 60 the upper flange and over the lower flange of the side sills 6 as shown in Fig. 14. The inner portion of the lower flange of the I beams is cut off as indicated at 51, Fig. 15, this cut-out portion extending from the center sills 3 outwardly to the side sills 6, thereby providing a clear space to receive and permit free movement of the truck side bearing 52. An H beam 53 corresponding to H beams 37 and 37', Figs. 7, 10 and 13, is supported against the inner surfaces 70 of the webs of I beams 43 and 44, thereby providing as shown in the previous modification a suitable support for a wearing plate 54 for the truck side bearings 52, in addition to providing a cooperative reinforcing action between the var- 75

ious parts. It will also be noted that the center pin 55, Fig. 14, is located and supported similar to that shown in Figs. 11 and 13.

A small filler plate 56, Figs. 11 and 13, extends 5 across and rests on the top of the center sills 3 and also extends between the flanges of the T's 12 and 13. In other words, such a filler plate rests in a recess 51, Fig. 7. The purpose of this 10 filler plate is to form a continuous top cover plate and to resist the compression strains therein. It will, of course, be understood that this plate is welded at all lines of juncture with the other component parts of the structure. Likewise all other component parts of the structure 15 are welded along their lines of juncture, although in some instances where leakproof joints are not necessary the welding may be either partially or wholly omitted depending upon the stress relation of the parts. It will be noted however, that 20 the various parts have been so formed and constructed and interrelated that they are conducive to efficient and effective welding of the parts so as to insure minimum weight consistent with maximum strength. As a further illustration of 25 the manner in which the parts are formed, so as to be conducive to strength, a bolster cover plate 58, Figs. 2 and 11, extends across the top flanges of T's 12 and 13 for a substantial portion of their length but terminating short thereof as indicated 30 at 59 in Fig. 2. The bolster cover plate 58 extends only over the rear bolster 11, Fig. 2. The forward bolster 10 is not provided with a cover plate 58 but has a longitudinally rectangular center sill top cover plate 60, Fig. 2, extending 35 from a T 61, Fig. 5, forwardly to the front end sill 4. It will be noted that the dimension between the edges 62 of this cover plate is less than that between the edges 59 of cover plate 58. The purpose of cover plate 60 is to form the bottom 40 of a stoker trough and to separate the trough from the surrounding water space. It will be understood that cover plate 60 is formed in three sections, one extending between T 61 and the left edge of bolster 10, Figs. 3 and 5, one extending 45 between the bolster T's 12 and 13 of forward bolster 10, and the other extending from the right edge of bolster 10 to the front end sill. These sections are necessitated due to the cross 50 T's of the bolster extending across the top of the center sill. The cover plate 58 above referred to has been omitted from Fig. 5 for purposes of clarity. This figure, however, does show a center sill cover plate 63 extending from T 61 to the forward T of the rear bolster 11 and 55 thence from the rear T of bolster 11 to the end sill 5 as indicated at 63', Fig. 5. The recess 57 between T's of bolster 11 has a filler plate 56 with a reinforcing plate 58 as previously described. The T 61, Figs. 1 and 5, forms a base 60 for the vertical end plate 61' of the stoker trough. The T is coped in similar manner to the top bolster T's 12 and 13, Fig. 8, and is positioned on center sills 3-3 before forward bolster 10 is assembled.

65 *Front draw bar housing.*—This is shown generally in end elevation in Fig. 3 and in the broken perspective of Fig. 16 while component parts are shown in Figs. 18 to 21. The housing comprises two vertical side pieces or sills 70 and 71, Figs. 18 and 21, a member having a combined bottom 72 and back 73, Fig. 19, and one intermediate member 74, Figs. 20 and 16. The side pieces are of generally triangular shape, their upper edges extending upwardly through longitudinal slots 75 formed in the lower cover plate

9 along the outer edges of the lower flanges of the two center sills 3. The upper edges of the side pieces are turned over the outer portion of the lower flanges of the side sills 3 as indicated at 76, Fig. 16. If desired, the flanges 76 may be preformed on the side pieces before assembling, in which case the side pieces would be assembled by initially placing them in a horizontal position and entering the flanges 76 in slots 75 and then working the same therethrough and over the 10 center sill flanges until the side pieces are in a vertical position. The intermediate plate 14 is next assembled with back portion 73 by extending a flanged tongue 78 through a suitable slot 79, Figs. 19 and 20. These members are then 15 inserted between the side pieces 70 and 71 and interconnected through suitable tongues 80 and slots 81. The upper edge of back 73 is also provided with a tongue 82 that extends upwardly through a slot 83, Fig. 16, between the inner 20 edges of the lower flanges of center sills 3, 3. The remaining vertical edge 84, Fig. 19, of the back piece 73 will thereupon abut against the lower cover plate 9. All of the foregoing pieces are then firmly held together and welded along 25 any or all of their lines of juncture or otherwise suitably secured.

Suitable drawbar pin bushings 86, Fig. 17, are set up in rectangular openings 87, Figs. 19 and 20 and provided with a slightly tapered forward 30 lip 88 on which the drawbar slides when the tender is connected to the engine. An uppermost bushing 89 is not provided with a lip such as 88 inasmuch as bushing 89 is received in a recess in the bottom cover 9 and inner flange of 35 the center sill 3.

Due to the stoker mechanism being located immediately above the drawbar pin, the pin must be inserted from below and held in place by a usual keeper plate (not shown). The plate is 40 normally inserted on top of a drawbar pin keeper strut 86', Fig. 16, said strut being positioned between the housing sides 70 and 71 and welded thereto. The strut has an opening 87' through which the drawbar pin is inserted before the 45 keeper plate is bolted in position on the strut.

To reinforce the side pieces 70 and 71, there is provided on the outer side of each a vertical angle iron 90 having suitable recesses 91 to permit tongues 80 to project through the openings 50 81 when assembled therewith. Tank valve wells 92 and 93, Fig. 3, are formed on each side of the side pieces 70 and 71. These wells are identical in construction, and hence the description of one will suffice for the other. As shown in Fig. 55 21, the well comprises a U-piece 94 having a valve opening 95. One end of the U-piece is closed by a combined end closure and bracket member 96 abutting against the edge of angle 90. The other end of the U-piece is closed by a 60 member 97, thereby completing the well. The upper edge of the well structure is suitably inclined so as to abut the under side of the inclined bottom 9 as shown in Fig. 3. A reinforcing bottom plate 98 may be provided at the bottom of 65 the well. All of the foregoing parts are welded together to form a single integral unit.

To provide a simplified spring buffer pocket, I have combined the same with my improved draft rigging housing side pieces 70 and 71 by extending the same forwardly and thence upwardly as indicated at 100, Figs. 18 and 21. The rear edges 101 of these projections extend vertically for contact with a spring abutment plate 102. This plate is supported against the forward ends of 75

the two center sills 3, 3 and between the upper flange of end sill 4 and a filler piece 103 which is inserted between the lower flange of the end sill and the bottom of the center sills. Top and bottom plates 104 and 105 are located between a projection 100 and abut against back plate 102, thereby forming a pocket for a buffer spring not shown. The forward ends of top and bottom plates 104 and 105 are rounded at their forward 10 end as at 106 while a reinforcing band 107 surrounds the outer end of the pocket. All of the foregoing parts are welded entirely or partly along their lines of juncture or otherwise suitably secured together.

15 Suitable lateral bracket members for the spring pocket are provided at 109 and 110, Fig. 3, located on each side of the pocket are shown in Fig. 3.

Rear draft rigging housing.—As shown in Fig. 6, the inner sides of the lower flanges of the center sills 3, 3 terminate at 112 and are slightly notched as at 113 to receive side pieces 114 and 115, Figs. 6 and 22. Inasmuch as the side pieces 114 and 115 are identical except that they are adapted for left and right hand positions, the description of one will suffice for both. The piece 114 has a lower horizontal flanged edge 116 and an inclined unflanged edge 117, Fig. 23. The upper edge of the side piece is provided with an outwardly turned flange 118 projecting through a suitable notch in the web of the center sill as shown in Fig. 22. A hole 119 is provided in the side piece and center sill web to permit flow of water therethrough. Lugs or stops 120, Figs. 6 and 23, for the follower plates of the usual type of draft rigging are positioned at the end of the lower horizontal flanged edge 116, or more precisely at the juncture of said edge and the inclined edge 117, Fig. 23. The stops 120 are provided with tongues 121 received in suitable notches in the side piece 114. To further reinforce the stops, a vertical plate 122, Fig. 6, is placed against the side face of member 114 while intermediate and lower brackets 123 and 124, Figs. 6 and 23, rest against plate 122 and stop 120. To reinforce the unflanged inclined edge 117, a rib 125 is secured to the inner side of side pieces 114. All of the foregoing parts are entirely or partially welded along their lines of juncture or otherwise suitably secured or formed together.

Outer follower plate stops 126, Fig. 6, are provided on the inner faces of each side piece 114 and 115. These stops are notched in said side pieces and are otherwise similar to the inner stops 120 except that a recess 127 is formed in stops 126 to permit full travel of the coupler key. Upper and lower vertical extending angle braces 128 are welded to side piece 114 and stop 126 for additional reinforcements thereof. The angle brackets 128 are spaced slightly apart to permit the coupler key to pass freely through its opening 129, and horizontal triangular pieces 128' (Figs. 6, 22 and 23) are welded between the edges of the coupler key opening and the ends of angle brackets 128.

The bottom cover plate 9 is of course slotted as at 130, Fig. 6, in alignment with the notches 113 to permit the side pieces 114 to extend upwardly through the bottom. The remaining center portion 131 of the bottom plate is bent upwardly and extends forwardly between the side pieces and rests upon the upper edges of the stops 120 and 126. This portion 131 terminates adjacent the outer vertical edge of the side pieces

114. The purpose of raising the elevation of member 131 is to permit the center line of the draft rigging to be located at the standard height. In certain cases it may not be necessary to raise the elevation of portion 131, in which case this would remain on the same plane as the remaining portion of bottom plate 9. To support the center offset portion 131, there is provided an angle iron 132, Fig. 6, welded to the bottom plate 9 and the inclined portion of the center member 131.

The center sills 3, Fig. 6, are inclined as at 135. Abutting against the entire ends of the end sills and extending down along the vertical edge of side pieces 114 is a combined striking plate and coupler carrying iron. The lower end of the plate 136 is flanged under as at 137, Fig. 23. A bracket 138 is disposed transversely behind the plate 136 to reinforce it where the horn of the coupler strikes a wearing plate 139. A 20 transverse angle piece 140 is supported upon the flange 137 and also upon the lower edge of a coupler opening 141 to act as a wearing plate for the coupler shank. A suitable triangular rib 142 may be positioned behind the angle piece 140 and 25 the lower edges of flanges 116 of side pieces 114 and 115. All of the foregoing parts are as previously mentioned many times, partially or entirely welded along their lines of juncture or otherwise suitably secured or formed together. 29

Suitable openings 150 are provided at any desirable location in the various members of the underframe so as to connect the several compartments formed between the structural members, thereby permitting the water to have free passage between said compartments and equalize the water level. 35

In Figs. 1 to 4, improved transversely disposed coal slide guide stiffeners or braces 143 are provided adjacent each transverse edge of a series of openings 146 in the coal space floor 145 overlying a usual chamber 146a in which a usual stoker conveyor (not shown) is disposed. As is customary, coal is fed by gravity successively through said openings which are opened one at a time by means of usual movable sectional slides 147 supported between guides 148 with their retaining plates 149. Heretofore these openings have not been reinforced because of the objection to obstructing or of retarding flow of coal to the openings and of making it difficult to shovel the coal from the coal space floor 145 in case the fireman is required to supplement the action of the stoker by touching up the fire. Hence the narrow strips of plate 145 between the several openings 146 have heretofore been subject to considerable vibration and stresses, resulting in leaks at the juncture between this floor sheet and the walls forming the water containing portions of the tank. To repair such leaks has increased maintenance costs. However, in my improved combination I overcome all of the foregoing objections by providing the braces 143 in the form of inverted angle irons disposed over each strip of floor plate left between openings 146, the ends of the angle iron being flattened as at 143a.

at 144 and welded to the floor plate 145. The flattened ends not only provide a large contact surface with the floor plate but also increase the available welding area between the angle iron and floor in the event that these members are welded together. By reason of the bevelled upper surface of these braces, they not only function to give maximum rigidity to the structure but also minimum obstruction to the flow 75

of coal through the openings 146 and also permit the edge of a shovel to readily pass thereover.

From the foregoing disclosure it is seen that I have provided a combination whose component elements are so formed and interrelated that their cooperative action effects a compact, sturdy and lightweight structure capable of insuring maximum water capacity together with maximum strength for the welded joints.

10 It will of course be understood that various changes in details of construction and arrangement of parts may be made by those skilled in the art without departing from the spirit of the invention as set forth in the appended claims.

15 I claim:

1. A car underframe comprising, in combination, a center sill, and a bolster having two sets of transverse members, said sets being longitudinally spaced apart and each set having upper and lower T-members located respectively above and below said center sill, the stems of said T-members being in opposed relation to each other, a transversely extending I-beam having its flanges operatively connected respectively to the stems of each set of T-members whereby the web of said I-beam lies horizontally, and side bearing means associated with the web of said I-beam whereby the truck side bearing projects upwardly between the lower T-members.

30 2. A car underframe comprising, in combination, an I-beam center sill, a bottom cover plate extending beneath said center sill, a forward draw bar housing having side pieces with flanged portions extending through said bottom cover, means for securing said side pieces to said center sill, and bottom and intermediate plates extending transversely between said side pieces and provided with a tongue and slot connection therewith.

40 3. The combination set forth in claim 2 further characterized by the provision of a drawbar pin bushing disposed in a recess formed in said bottom cover, and other similar bushings disposed in recesses in the plates which are connected to the side pieces.

45 4. A car underframe comprising, in combination, a center sill and end sill, a forward drawbar housing having side pieces supported by said center sill and plates extending transversely between and connected to said side pieces, said side pieces each having a forwardly and upwardly projecting portion to form the sides of a buffer spring pocket, and transverse top and bottom plates disposed between said portions to complete said pocket.

50 5. A car underframe comprising, in combination, an I-beam end sill having an opening in its web, a center sill extending through said opening, a forward draw bar housing supported by said center sill and having side piece portions extending forward and upwardly in front of the end of said center sill, top and bottom plates disposed transversely between said portions to form a buffer spring pocket, and means providing a backing wall for said pocket against the end of said center sill.

55 6. A car underframe comprising, in combination, an end sill having an opening therein, a pair of parallel I-beams forming a center sill extending through said opening, a pair of side pieces supported by the inner sides of said I-

beams to form a rear draft rigging housing, and a plate extending down across the ends of said I-beams and side pieces.

7. The combination set forth in claim 6 further characterized by the provision of follower plate stops formed on the inner surface of each of said side pieces, and a lower plate cover extending beneath said center sill and having a portion extending over the top of said stops.

8. The combination set forth in claim 6 further characterized in that the inner sides of the lower flanges of the center sill I-beams are cut away, whereby said side pieces lie flush against the web of said I-beams.

9. A tender underframe comprising, in combination, a structural center sill having upper and lower horizontal flanges, structural channel members forming side sills with upper and lower substantially horizontal flanges, bolsters connecting said center and side sills, and a substantially flat plate metal water bottom cover for carrying the water load of the tender, said plate cover extending continuously from one side sill to the other side sill and resting on the top of the lower side sill channel flanges and extending beneath and in contact with the under side of the lower horizontal flange of the center sill, said bottom plate being secured to said center sill lower flange to be supported thereby and being welded to the lower side sill channel flange.

10. A tender underframe comprising, in combination, a structural center sill having upper and lower horizontal flanges, structural channel side sills having upper and lower flanges whose lower flange is tapered so as to have an upper surface inclined downwardly toward the lower portion of the center sill, bolsters connecting said center and side sills, and a substantially flat plate metal water bottom cover for carrying the water load of the tender, said plate cover extending continuously from one side sill to the other side sill and resting on the inclined upper surface of the lower side sill flange and extending beneath and in substantial supporting engagement with the under side of the lower horizontal flange of the center sill, said bottom plate being welded to said center and side sills.

11. The combination set forth in claim 9 further characterized in that the lower flanges of said side sills are located above the horizontal plane of the lower horizontal flange of the center sill, and the bolster is formed of upper and lower T members with their stems in opposed relation to each other, the lower T member being so formed adjacent the side sills that the flange of the lower T member and the lower flanges of the side sills lie substantially in a common horizontal plane, and the transverse edge of the plate metal bottom cover in extending continuously from one side sill to the other side sill rests on the upper surface of the flanges of the lower T member.

12. The combination set forth in claim 9 further characterized in that the bolster has a lower horizontal flange extending substantially from the center sill to the side sills and the transverse edge of said plate metal bottom cover in extending continuously from one side sill to the other side sill rests on top of said bolster flange, the plate metal bottom cover being welded to the bolster flange.
